UNITED STATES PATENT OFFICE

1,957,826

SHINGLE

Donald F. Fradette, Cleveland, Ohio

Application April 14, 1932, Serial No. 605,256

6 Claims. (Cl. 108—7)

This invention relates to improvements in shingles, particularly designed to be used as a roof-
ing or wall covering unit, the butt of the shing-
le or that portion exposed to the weather be-
ing of porcelain-enamel construction or other
5 suitable metal such as brass, bronze, yellow metal,
copper, white metal, and acid-proof and other
corrosion-resisting alloys. The enamel may be
flexible if desired.

10 According to the present invention, a shingle is provided with a porcelain-enamel or foliated noncorrosive metal butt fixed to a base of pliant composition impervious to water, and also re-
sistant to solar heat.

15 Also, according to the present invention a de-
pendable and highly efficient shingle is provided
for use in conjunction with roofs and walls in
all types of structures where a roof or wall of
this type may be applicable, and the roof or wall
20 or both may be made to congrue with the aes-
thetic or artistic discernment of a builder or
owner.

25 Various further and also various more spe-
cific objects, features, and advantages will more
clearly appear from the detailed description
given below taken in connection with the ac-
companying drawing which forms a part of this
specification.

The invention consists in such novel features,
30 arrangement and combination of parts and meth-
ods as may be shown, described and claimed in
connection with the embodiment of the inven-
tion herein disclosed by way of example only.

35 Constructional examples of the invention are
illustrated in the figures, in which:—

Fig. 1 is a top plan view of a shingle unit
embodiment of my invention.

Fig. 2 is a side or edge elevation of a modified
40 form of a shingle, the reinforcing wire being
omitted, otherwise the construction is the same
as that shown in Fig. 1.

Fig. 3 is a fragmentary side or edge sectional
view of another modified form of a shingle on
45 a larger scale, showing the same provided with
a reinforcing wire, and also a reinforcing fabric
over a portion of the base that is bent back upon
itself to form the sealing means for the joint
formed by the butt and the base.

Fig. 4 is a fragmentary plan view of the butt
50 detached from the base to show the laterally
disposed notches therein.

Fig. 5 is a perspective view of the reinforcing
element detached from the shingle proper and
showing how it may be constructed.

55 In the drawing like characters of reference in-

dicate corresponding parts in the several fig-
ures.

Referring to Fig. 1 illustrating a shingle, the
shingle base 10 which in these illustrations is
shown as a strip of flexible impervious water re-
sisting material is flexed or bent over an enam-
eled butt 11, and cemented or otherwise secured
or attached thereto as at 12. A reinforcing wire,
rod, cord or rope 13 is positioned transversally in
the loop formed in the base substantially as 65
shown, and the base is then bent back upon itself,
and the loop thus formed is secured in any suit-
able manner as by cementing. The reinforcing
element 13 may be bent over and under the base
and secured in any suitable practical manner. 70
The ridge, protuberance or projection 14 formed
by the bending of the base upon itself forms one
of the elements of the interlocking instrumental-
ities hereinafter described.

The butt of the shingle is provided with a ledge 75
15 that may extend transverse of the shingle base,
and may be provided with spines, spurs, spikes
or other suitably pointed elements 16 and 17
that may engage under the ridge or protuberance
formed on the base. 80

Adjacent the ledge 15 there is provided a gap
or trench 18, this gap or trench is formed by
stopping short the base 10 in proximity to the
ledge, and has a depth equal to the mean thick-
ness of two folds of the base that forms the ridge 85
or protuberance.

The spines are adapted and arranged to engage
in the ridge or under same, and forms with the
ridge the other member of the interlocking in-
strumentality when the shingles are imbricated 90
in the usual well known manner.

The wire reinforcing member is provided to
prevent fracture of the ridge that might be caused
by the engagement therein or therewith, and also
to prevent the ridge from becoming detached 95
from the butt and thus allowing the water to seep
into and under the ridge and percolate through
the joint formed by the base and the butt that is
sealed under the ridge. The shingle butt is also
provided with laterally positioned notches, holes 100
or apertures 19 and 20 to allow for the passage
of nails therethrough in securing the shingles,
the same being provided to prevent fracture of
the enamel or metal butt in the process of at-
taching the shingles to a roof or wall. 105

A layer of fabric 21 may be employed to rein-
force the ridge or protuberance if desired.

While the invention has been described in de-
tail with respect to certain particular preferred
examples which gives satisfactory results, it will 110

be understood by those skilled in the art after understanding the invention that various changes and modifications may be made without departing from the spirit and scope of the invention, 5 and it is intended therefore in the appended claims to cover all such changes and modifications.

What I claim as my invention and desire to secure by Letters Patent is:—

- 10 1. A shingle comprising: a flexible base with an enameled butt, the base bent upon itself to form two loops, one of the said loops having mounted and sealed therein an end portion of the butt, the butt being attached to the base throughout at least a major portion of its length, a ledge integrally formed on the butt having spines associated therewith, a reinforcing means interposed in the other loop and cooperating with the base whereby the base is strengthened at that 20 portion wherein the loops are formed.
2. A shingle comprising: a flexible base with a flexible enameled butt, the base bent upon itself to form two loops, one of the said loops having mounted and sealed therein an end portion of the 25 butt, the end portion of the butt having laterally disposed notches therein, the butt being attached to the base throughout at least a major portion of its length, a ledge on the butt having spines attached thereto, and a metallic reinforcing element in the other loop and cooperating with the base whereby the base is strengthened at the portion of the base having loops formed therein.
3. A shingle comprising: a flexible base with 30 an enameled butt, the base bent upon itself to form a plurality of loops, one of the said loops

having mounted and sealed therein an end portion of the butt, the said end portion being laterally notched, the butt being attached to the base throughout the major portion of its length, the butt also being provided with a ledge having spines spaced thereon, the other loop cooperating with the base, and means whereby the loops are maintained in effective relationship.

4. A shingle comprising: a flexible base with an enameled butt, the base bent upon itself to form two loops, one of the said loops having mounted and sealed therein an end portion of the butt, the said end portion having laterally positioned apertures therein, the butt being attached to the base throughout a major portion of its length, the butt also being provided with a ledge having a plurality of inwardly directed spines therealong, a reinforcing fabric in the loops cooperating with the base whereby the base is strengthened at that portion wherein the loops are formed.

5. A shingle comprising: a pliant base flexed upon itself, having attached thereto an enameled butt which forms with the base a joint sealed under and by the flexed portion of the base; a reinforcing member transverse of the base, interposed between a flexed portion of the base, and extending over edge portions of, and under the base, notches laterally positioned in the butt, positioned under the flexed sealing portion of the base; a ledge on the butt; and spear points operatively associated with the ledge.

6. A shingle as defined by claim 5 further characterized in having a gap positioned between the ledge on the butt and the end of the base.
